UNITED STATES PATENT OFFICE

BARTOLOMEO ELIGGI, OF SAN FRANCISCO, CALIFORNIA

DESIGN FOR A DIRECTION INDICATOR

Application filed May 23, 1930. Serial No. 35,730. Term of patent 14 years.

To all whom it may concern:

Be it known that I, BARTOLOMEO ELIGGI, a subject of the King of Italy, residing at San Francisco, in the county of San Francisco and State of California, have invented a new, original, and ornamental Design for Direction Indicators, of which the following is a specification, reference being had to the accompanying drawing, forming a part thereof.

The figure is a perspective view of a direction indicator showing my new design.

I claim:—

The ornamental design for a direction indicator substantially as shown.

BARTOLOMEO ELIGGI.
